UNITED STATES PATENT OFFICE.

ALBERT FRANZ HEINRICH HAMANN, OF HAMBURG, GERMANY.

CASEMENT OR FOLDING WINDOW.

No. 887,936.

Specification of Letters Patent.

Patented May 19, 1908.

Application filed October 19, 1907. Serial No. 398,159.

To all whom it may concern:

Be it known that I, ALBERT FRANZ HEINRICH HAMANN, a subject of the German Emperor, and resident of Hamburg, Germany, have invented certain new and useful Improvements in Casements or Folding Windows, of which the following is a specification.

This invention relates to improvements in casements or folding windows having a casement or casements adapted to be turned or swung in both directions, that is to say, inwardly and outwardly. On account of its novel arrangement, actuated in an extremely simple and convenient manner not only is a better and more complete closure against drafts and water obtained by the improved construction, but the casements or valves when turned or folded inward, may be also brought together into position to allow of ventilation of the room.

The window is characterized in that besides the well known intermediate vertically hanging stiles hinged to the casement frame and carrying the casements, horizontal upper and lower beads or rabbet bars are hinged to the casement frame in such manner that they may be folded or turned between the movable stiles so as to clamp the latter and form in conjunction therewith the complete intermediate abutment frame for the casements. The horizontal bars may also be fixed to the stiles by suitable means during the ordinary use of the casements.

By the arrangement of the four stiles hinged to the window frame a special fastening device for the two vertical stiles carrying the wings is dispensed with, as these latter stiles are held in their proper position against the window frame by the lower and upper horizontal stiles or bars fitting with the end faces snugly between the vertical stiles and pressing them tightly against the window frame. In order to fold or turn the casements inwardly, it is only necessary to fold back or inward the upper and lower stiles or bars whereon the casements and the vertical strips carrying them can be turned inward.

In the accompanying drawing Figure 1 is an elevation of the improved folding window seen from inside; in this position of the parts the wings or casements are adapted to be folded outwardly. Fig. 2 is a vertical and Fig. 3 is a horizontal section. Fig. 4 is a

horizontal section with inwardly turned wings or casements brought together for the purpose of ventilation.

On the inside of the window frame *a* vertical stiles *b* of known form are arranged to fold inwardly by means of hinges *c* and horizontal bars *d* (above and below) by means of the hinges *e*. The stiles or bars *b* and *d* form when folded against the window frame *a* in the manner shown in Figs. 2 and 3, a continuation of such frame and at the same time the tongue for the casements or valves *f* (Figs. 2 and 3). The stiles *b* are secured in the position shown in Figs. 1 and 3 and held tightly against the inner wall of the window frame *a* by the bars *d* engaging between the stiles *b* and exactly fitting the same. The bars *d* are held in position by the friction between their ends and the stiles *b*. If desired they may moreover be secured in this position by sliding bolts *g* arranged at the ends of the bars *d* and engaging suitable recesses in the stiles *b*. To obtain a tight closure between the stiles or bars *b*, *d* and the window frame *a*, the contacting surfaces are grooved or rabbeted to engage or interfit with one another.

To the outside faces of the stiles *b* the window casements *f* are rotatably attached by means of hinges *h*; the casements *f* may be provided with suitable closing means (not shown) engaging in the bars *d* and pressing the casements *f* against the stiles or bars *b* and *d*.

In order to allow of inward turning of the casements or wings *f* the bars *d* are folded inward, as shown in dotted lines in Fig. 2 and in full lines in Fig. 4, whereby the stiles *b* are released so that the casements and the thus freed stiles *b* may be swung or turned inward. When in this inward turned position of the stiles *b* the casements *f* are closed, so that the edges of the casement frames meet in the center, as is shown in Fig. 4, the free window aperture remains closed, but an upper and lower slot like opening is left for ventilation of the room between the closed casements and the window frame. In this position of the casements the outside of the same is likewise directed outward. The wings can be detached from their hinges in both their outer and inner positions.

I claim:—

A window casing having stiles abutting the sides of the casing, hinges connecting the stiles with the casing, casements hinged to the stiles, a bottom bead and a top bead hinged to the casing and fitting between and contacting with the stiles so as to clamp the latter and form in conjunction therewith a complete intermediate abutment frame for the casements.

ALBERT FRANZ HEINRICH HAMANN.
